Primary Examiner — Austin Murphy(74) *Attorney, Agent, or Firm* — Paratus Law Group, PLLC(57) **CLAIM**

The ornamental design for a stylus holder, as shown and described.

DESCRIPTION

FIG. 1 is a front, top, and right-side perspective view of a stylus holder, showing my new design;

FIG. 2 is a front view thereof;

FIG. 3 is a back view thereof;

FIG. 4 is an enlarged left-side view thereof;

FIG. 5 is an enlarged right-side view thereof;

FIG. 6 is a top view thereof;

FIG. 7 is a bottom view thereof;

FIG. 8 is a back, top, and left-side perspective view thereof;

FIG. 9 is a front, top, and right-side perspective view thereof, showing the stylus holder in a configuration of use; and,

FIG. 10 is a back, top, and left-side perspective view thereof, showing the stylus holder in a configuration of use.

The broken lines shown in FIGS. 9 and 10 depict environmental subject matter only and form no part of the claimed design.

1 Claim, 6 Drawing Sheets(56)
